UNITED STATES PATENT OFFICE.

VERNON DURBIN, OF NEWTON, AND HENRY EHRISMANN, OF BOSTON, MASSACHUSETTS, ASSIGNORS TO THE HOLTZER-CABOT ELECTRIC COMPANY, OF BROOKLINE, MASSACHUSETTS.

CIRCUIT-CLOSER.

1,117,646.

Specification of Letters Patent.

Patented Nov. 17, 1914.

Application filed May 9, 1913. Serial No. 766,539.

To all whom it may concern:

Be it known that we, VERNON DURBIN and HENRY EHRISMANN, citizens of the United States, and residents of Newton, in the county of Middlesex, and of Boston, in the county of Suffolk, respectively, and State of Massachusetts, have invented a new and useful Improvement in Circuit-Closers, of which the following is a specification.

Our invention relates to push-button circuit-closers and especially to those of the self-locking type which are adapted for use in hospital signaling systems, and the object of our invention is to improve and simplify the construction thereof in the manner hereinafter set forth.

One embodiment of our invention is shown in the drawings which accompany and form a part of this specification, but it will be understood that we do not limit ourselves to the particular form shown inasmuch as various modifications may be made therein by those skilled in the art without departing from the spirit of our invention.

In the drawings,—Figure 1 is an elevation of a push-button circuit-closer made in accordance with the present invention, the casing being shown in section. Fig. 2 is a central vertical section taken on the line 2—2 of Fig. 5. Fig. 3 is a central vertical section taken on the line 3—3 of Fig. 5. Fig. 4 is an elevation with the casing shown in section illustrating the manner of unlocking the circuit-closer by a key. Fig. 5 is a plan view with the casing removed.

In the particular drawings selected for more fully disclosing our invention, 1 represents a casing of insulating material such as vulcanite, arranged to receive at its lower end a plug 2, secured thereto by screws which pass through holes in the casing and corresponding holes, one of which is shown at 3 in the stem 4 which is formed integral with the plug and which carries the spring-finger circuit-closing elements.

In the present instance three spring-fingers 5 of copper are shown, each secured in one of the grooves 17 of the stem by means of screws, and each provided with a backing plate 5' of brass. We prefer to employ a fourth spring-finger 6 which, being slightly shorter than the fingers 5, terminates

below the ends thereof and has a backing 55 plate 6'.

Secured to the stem at diametrically opposite points are two latching members 7 of suitable spring material, the upper ends of which are suitably shaped to limit the upper movement of the circuit-closer and also to hold the same in circuit-closing position.

A pin 9 is suitably attached to the push-button 10 and resilient means such as the spiral spring 9' surrounding said pin and having its ends in recesses in the push-button and stem respectively serves to maintain the circuit-closer normally in circuit-opening position.

The lower portion of the push-button consists of a polyangular member 12 of insulating material, herein shown as having four sides, and the contact-maker 11 of brass or other conducting material is supported on the portion 12 of the push-button. The contact-maker is shown in the present instance as a squared brass plate having its corners cut away for the purpose of permitting the down turned ends of the latching members to come in contact with opposite corners of the squared member 12, as shown in Figs. 1 and 5.

Surrounding the push-button and arranged within the bushing 14 of the casing 85 is a collar 13 having a cone-shaped lower portion.

For the purpose of guiding the push-button, a pin 16 depending from the member 12 and taking into a hole in the stem 4 may be 90 employed. Suitable conductors 8 passing through a hole in the plug and branching perforations communicating therewith are attached as by screws to the four circuit-closing spring-fingers.

In its normal position the contact-maker is out of electrical connection with the spring-fingers, and the latching members, against the ends of which the spring 9' forces the squared portion 12 of the push-button, hold the latter and its attached contact-maker in the position shown in Fig. 1.

When the push-button is depressed, the spring-fingers 5 make electrical contact with the contact-maker and the ends of the latching members spring inwardly, so that when the pressure on the push-button is released, they serve to hold the contact-maker in cir-

2

cuit-closing position as shown in Fig. 3. In this position the circuits connected with the fingers 5 are electrically connected through the contact-maker and operate lights or other signaling devices in the corridor of the hospital, or superintendent's office, or both, as the case may be. A slight further depression of the push-button will, without moving the contact-maker 11 out of engagement with the fingers 5, bring the spring-finger 6 also into electrical connection with said contact-maker and will close the circuit of a buzzer or other audible signaling device. This is accomplished in the present instance by making the interval between the upper end of the spring-finger or circuit-closing element 6 and the upper ends of the spring-fingers 5 shorter than the length of the contact-maker 11, as clearly shown in Fig. 4. When this pressure is released, the parts again take the position shown in Fig. 3. When the call has been answered, the push-button is unlocked by means of a key or other suitable implement, such as that shown at 15, which fits over the upper end of the push-button and forces the collar 13 downwardly, so that its flaring end spreads the latching members 7 as shown in Fig. 4. It will be obvious that when the key is removed, the contact-maker will slide past the latches on the latching members and the ends of the latter will again come in contact with the corners of the squared member 12 as shown in Fig. 1, thereby holding the parts in circuit-opening position.

We claim:

1. A push-button circuit-closer comprising in combination a tubular casing, a longitudinally-bored stem secured within said casing, circuit-closing spring-fingers carried by said stem, a pin having its lower portion arranged within the bore of said stem, a push-button secured to the upper portion of said pin and extending beyond said casing, a contact-maker carried by said push-button, resilient means for normally maintaining said contact-maker out of contact with said spring-fingers, latching members for holding said contact-maker in circuit-closing position, and key-controlled means coöperating with said latching members for releasing said contact-maker from such circuit-closing position.
2. A push-button circuit-closer comprising in combination a casing, a stem secured within said casing, circuit-closing spring-fingers carried by said stem, a pin movable with respect to said stem, a push-button secured to the upper portion of said pin, a contact-maker carried by said push-button, resilient means for normally maintaining said contact-maker in circuit-opening position, latching members for holding said contact-maker in circuit-closing position, and key-controlled means coöperating with said

latching means for releasing said contact-maker from said circuit-closing position.

3. A push-button circuit-closer comprising in combination a tubular casing, a longitudinally-bored stem secured within said casing, circuit-closing spring-fingers carried by said stem, a pin having its lower portion arranged within the bore of said stem, a push-button secured to the upper portion of said pin and extending beyond said casing, a contact-maker carried by said push-button, resilient means for normally maintaining said contact-maker out of contact with said spring-fingers, latching members for holding said contact-maker in circuit-closing position with respect to said spring-fingers, and a circuit-closing element out of electrical connection with said contact-maker when the latter is held by said latching members in said circuit-closing position, said circuit-closing element terminating below the upper ends of said spring-fingers and coöperating with said contact-maker upon further depression of the latter.

4. A push-button circuit-closer comprising in combination, a tubular casing, a longitudinally-bored stem secured within said casing, circuit-closing spring-fingers carried by said stem, a pin having its lower portion arranged within the bore of said stem, a push-button secured to the upper portion of said pin and extending beyond said casing, a contact-maker carried by said push-button, resilient means for normally maintaining said contact-maker out of contact with said spring-fingers, latching members for holding said contact-maker in circuit-closing position with respect to said spring-fingers, a circuit-closing element out of electrical connection with said contact-maker when the latter is held by said latching members in said circuit-closing position, the said circuit-closing element terminating below the upper ends of said spring-fingers and coöperating with said contact-maker upon further depression of the latter, and key-controlled means for releasing said contact-maker from said circuit-closing position.

5. A push-button circuit-closer comprising in combination a casing, a stem secured within said casing, circuit-closing spring-fingers carried by said stem, a pin movable with respect to said stem, a push-button secured to the upper portion of said pin, a contact-maker carried by said push-button, resilient means for normally maintaining said contact-maker in circuit-opening position, latching members for holding said contact-maker in circuit-closing position with respect to said spring-closing fingers, and a circuit-closing element terminating below the upper ends of said spring-fingers, the interval between the upper end of said circuit-closing element and the upper ends of

said spring-fingers being shorter than the length of said contact-maker.

6. A push-button circuit-closer comprising in combination a casing, a stem secured within said casing, circuit-closing spring-fingers carried by said stem, a pin movable with respect to said stem, a push button secured to the upper portion of said pin, a contact-maker carried by said push-button, 10 resilient means for normally maintaining said contact-maker in circuit-opening position, latching members for holding said contact-maker in circuit-closing position with respect to said spring-closing fingers, a circuit-closing element terminating below the upper ends of said spring-fingers, the interval between the upper end of said circuit-closing element and the upper ends of said spring-fingers being shorter than the length 15 20 of said contact-maker, and key-controlled means for releasing said contact-maker from said circuit-closing position.

7. A push-button circuit-closer comprising in combination a casing, circuit-closing spring-fingers located inside said casing, a push-button, a contact-maker operated by said push-button, means for normally maintaining said contact-maker in circuit-opening position, latching members for holding 25 30 said contact-maker in circuit-closing position with respect to said circuit-closing spring-fingers, and a circuit-closing element

terminating below the upper ends of said spring-fingers and coöperating with said contact-maker upon further depression of the latter, the interval between the upper ends of said circuit-closing element and the upper ends of said spring-fingers being shorter than the length of said contact- 35 40 maker.

8. A push-button circuit-closer comprising in combination a casing, circuit-closing spring-fingers located inside said casing, a push-button, a contact-maker operated by said push-button, means for normally maintaining said contact-maker in circuit-opening position, latching members for holding said contact-maker in circuit-closing position with respect to said circuit-closing spring-fingers, a circuit-closing element terminating below the upper ends of said spring-fingers, and coöperating with said contact-maker upon further depression of the latter, and key-controlled means for releasing said contact-maker from said circuit-closing position. 45 50 55

In testimony whereof, we have hereunto subscribed our names this 8th day of May, 1913.
